ATTORNEYS,

UNITED STATES PATENT OFFICE.

FRANCIS T. RUSSELL, OF MINNEAPOLIS, MINNESOTA.

CAR-COUPING.

SPECIFICATION forming part of Letters Patent No. 485,061, dated October 25, 1892.

Application filed February 19, 1892. Serial No. 422,096. (No model.)

To all whom it may concern:

Be it known that I, FRANCIS T. RUSSELL, of Minneapolis, in the county of Hennepin and State of Minnesota, have invented a new and 5 useful Improvement in Car-Couplers, of which the following is a full, clear, and exact description.

My invention relates to an improvement in car-couplers, and has for its object to provide 10 a coupler capable of being set in such a manner as to automatically couple with an opposing coupler.

A further object of the invention is to so construct the draw-head that the link may be 15 supported in a horizontal position, and, further, to so locate and construct the supporting mechanism of the link that it will be brought into action immediately upon the lowering of the coupling-pin.

20 The invention consists in the novel construction and combination of the several parts, as will be hereinafter fully set forth, and pointed out in the claims.

Reference is to be had to the accompanying 25 drawings, forming a part of this specification, in which similar figures and letters of reference indicate corresponding parts in all the views.

Figure 1 is a longitudinal vertical section 30 taken through two opposed couplers, practically upon the line 1 1 of Fig. 2, and illustrating the manner in which a coupling is effected. Fig. 2 is a plan view of the opposed couplers, shown in Fig. 1, the coupling-pins being in 35 section, as indicated by the line 2 2 of Fig. 1; and Fig. 3 is a front elevation of the improved coupler, the link being in cross-section, as indicated by the line 3 3 of Fig. 1.

The draw-head A is adapted to be located 40 beneath a car in the ordinary manner, and may be attached to the car through the medium of any of the devices usually employed for that purpose.

The draw-head is provided with a link-opening 45 10 in its front face. The side walls of this link-opening are made to diverge from the outer face of the draw-head inward, and the top and bottom walls of the said opening are inclined one upward and the other downward, also in direction of the inner portion of the draw-head. Thus the link-opening 10 may be said to be practically wedge-shaped.

The link-opening 10 is bisected by a pin-aperture 11, which extends through from top to bottom of the draw-head, and the pin 12, 55 adapted to be located in the said aperture, is preferably circular in cross-section, and is provided at a point between its center and lower end with a recess 13, as is best shown in Fig. 1. A housing 14 is erected upon the 60 upper face of the draw-head immediately over the aperture in which the coupling-pin has movement, and in opposite walls of the housing vertical slots or slideways 15 are produced, in which slots or slideways an arm 16 is located, the said arm being secured in any appropriate manner to the coupling-pin at or near its upper end. The arm 16 extends beyond both ends of the coupling-pin and beyond the outer slotted faces of the housing, and the 70 said arm at its outer ends is provided with weights 17, attached thereto, the said weights acting normally to maintain the coupling-pin in its lower or coupling position. The coupling-pin has attached at its upper end one end 75 of a chain 18. This chain extends upward through the top of the housing over a pulley 19, journaled in the latter, and also over pulleys 20 and 21, attached to the end of the car. The chain may be led upward to be operated 80 from the top of the car, and outward to be manipulated from the side, or the chain may be provided with branches, whereby the coupling-pin 12 may be elevated either from the top or the sides of a car. 85

In the lower wall of the link-opening 10 a recess 22 is made, the said recess being preferably located near the front wall of the opening, and the recess is adapted to receive a shoe 23, capable when in its lower position, 90 of being flush with the lower wall of the opening, or practically so. The shoe has attached thereto or formed integrally therewith a downwardly-extending stem 24, whereby the shoe, including its stem, may be said to be substantially T-shaped, and the lower end of the stem of the shoe is pivotally attached to the forward end of a lever 25, fulcrumed beneath the draw-head, the lever being pivoted at or near its center in such a manner as to admit 95 of the rear end of the lever extending rearward beneath the coupling-pin aperture 11, as is best shown at the left in Fig. 1. When the coupling-pin is in its lower or coupling 100

position, the lower extremity of the pin bears upon the inner end of the lever 25 in such manner as to compel the shoe 23 to move vertically upward and remain in a position at an elevation above the base-wall of the link-aperture 10, as best indicated at the right in Fig. 1. The elevation of the shoe is such that it will hold the link 26, with which it is intended to engage, in a horizontal position, so that it will be directed to properly enter the link-opening of an opposed draw-head, and the said link is maintained in such horizontal position. After the pin is raised it is desirable that it should be held in its elevated position in order that a coupling may be effected with an opposing draw-head, and it is further desirable that when two draw-heads are brought together the coupling-pin will be automatically released from its latch and suffered to drop to a coupling position. To that end an angular latch 27 is held to slide in the top of the draw-head in a suitable chamber formed therein, and one end of this latch is held normally in engagement with the coupling-pin through the medium of a spring 28 of any approved formation. The latch is preferably provided with a recess 29, which normally receives a bolt 30, held to slide upon the top of the draw-head, which bolt is pressed by a spring, preferably by a portion of the spring 28. The bolt 30 may be drawn out of engagement with the latch 29 through the medium of a lever 31 and a link or links 32, connected with the bolt and with the lever. The lever 31 may be of the elbow type, and when so formed one end extends vertically upward in the path of the chain 18, utilized to elevate the coupling-pin. In fact the chain passes through an opening in this lever, and when the pin has been raised a proper distance the lever is operated by a button 33, attached to the chain, which at that time will be brought in engagement with the lever.

In Fig. 3 I have illustrated a lever as practically straight, and the connection between the bolt and the lever is made by three pivotally-connected links.

In the operation of the coupling the coupling-pin is drawn upward by the manipulation of the chain 18, and when the button 33 comes in engagement with the lever 31, as heretofore stated, the coupling-pin will be at its elevated position; and by moving the lever out in direction of the side of the car the bolt 30 is disconnected from the recess 29 in the latch 27 and the spring 28 will act upon the latch to force it into the recess 13 in the coupling-pin, as shown at the left in Fig. 1, as the said recess will be in position to receive the latch. When the link of the opposed draw-head enters the link-opening in the draw-head having the elevated coupling-pin, the outer ends of the latches 27 will engage with the draw-head of the opposed coupler, and the said latch will be forced inward, thus freeing the coupling-pin from the latch and permitting the latter to drop by its own

gravity downward into its opening 11 and through the link 26. It will be understood that when the inner end of the latch enters the recess 13 in the coupling-pin the outer end of the latch will extend beyond the outer face of the draw-head a distance equivalent to the depth of the recess. It will thus be observed that the car-coupler is not only simple, durable, and economic in construction, but that when set it will couple automatically with an opposed coupler, and, further, that the link will be at all times supported in a horizontal position when the coupler, is in connection with an opposed coupler, and whereby, also, the coupling-pin will be automatically released the moment that two draw-heads are brought in engagement.

Having thus described my invention, I claim as new and desire to secure by Letters Patent—

1. The combination, with a draw-head, of a coupling-pin held to slide in the draw-head and a shoe located in the link-opening of the draw-head and operated from the coupling-pin, substantially as shown and described.

2. The combination, with a draw-head and the coupling-pin thereof, of a shoe held to slide vertically in the link-opening of the draw-head and a lever connection between the shoe and the coupling-pin, as and for the purpose set forth.

3. In a car-coupler, the combination, with a draw-head and its coupling-pin, of a spring-pressed angular latch held to slide in the draw-head and engaging the coupling-pin to hold it elevated, said latch being provided with a recess, and a spring-pressed bolt in the front of the draw-head and adapted to engage the recess of the latch to hold it out of engagement with the coupling-pin, substantially as herein shown and described.

4. In a car-coupler, the combination, with the draw-head and a coupling-pin held to slide in the draw-head, weights attached to the upper end of the coupling-pin, and an elevating mechanism connected with the said pin, of a spring-controlled latch, the inner end of which is adapted for constant engagement with the coupling-pin, and a bolt acting in conjunction with the latch, substantially as and for the purpose specified.

5. In a car-coupler, the combination, with a draw-head and a weighted coupling-pin having movement in the draw-head and provided with a slot near one end, of a shoe having vertical movement in the link-opening of the draw-head, a lever connection between the shoe and the coupling-pin when the latter is in its lower position, a spring-controlled latch, one end of which is in constant engagement with the coupling-pin, and a spring-controlled bolt operating in conjunction with the latch, as and for the purpose specified.

6. In a car-coupler, the combination, with a draw-head and a weighted pin having vertical movement in the draw-head and provided with a recess in one face between the center

and its ends, of a mechanism for elevating the coupling-pin, a shoe capable of vertical movement in the link-chamber of the draw-head, a lever connection between the shoe and the link, a latch having sliding movement in the top of the draw-head, the inner end of which latch is in constant engagement with the coupling-pin, a bolt engaging with the

latch, and a means, substantially as shown and described, for operating the bolt when the coupling-pin is at its highest or elevated position, as and for the purpose specified.
